UNITED STATES PATENT OFFICE.

PERCY E. BROWN, OF THREE OAKS, MICHIGAN, ASSIGNOR TO THE WARREN FEATHER-BONE COMPANY, OF THREE OAKS, MICHIGAN, A CORPORATION OF MICHIGAN.

GARMENT-TRIMMING MATERIAL.

Application filed March 8, 1923. Serial No. 623,665.

To all whom it may concern:

Be it known that I, Percy E. Brown, a citizen of the United States, and a resident of Three Oaks, in the county of Berrien and State of Michigan, have invented certain new and useful Improvements in Garment-Trimming Materials, of which the following is a specification.

This invention relates to improvement in garment trimming material, as a new article of manufacture for the trimming of dresses, and like garments.

The product herein disclosed is used for the same general purpose as is braid, lace, and like materials, but differing essentially therefrom in that it is the result of a manufacturing process wherein ribbon, and like textiles forms the basis of the trimming.

In disclosing the invention the process of manufacture as well as the finished product will be set forth, reference being had to the accompanying drawings, wherein,

Figure 1 shows a length of ribbon in its initial form;

Figure 2 shows the ribbon after being cut for the folding operation;

Figure 3 shows the ribbon partially folded and stitched;

Figure 4 shows the completed trimming.

Considering the product as an article of manufacture, it is essentially a narrow tape-like material such as would be produced in indeterminate lengths, and to be sold by the yard as is ribbon and like textiles. In appearance it resembles a multitude of triangular or pyramid shaped sections A extended end to end, and joined together along their bases by a continuous reinforcing strip or binding B. Each of the triangular sections A is of a double thickness of material with folded edges along the two free or exposed margins thereof. This formation is attained by a novel method of cutting, folding and stitching now to be set forth in detail.

The basic material used in making the trimming is ribbon, tape, or like material having as its chief characteristic the bound or selvedged edges. As is customary in the production of trimming materials, the process of manufacture is a continuous one, the length of the finished material being determined by the method in which it is prepared for the market.

Considering then a strip of ribbon (Figure 1) as being of any length, and of a

width, of say, three-quarters of an inch, the first step in the manufacture, is to cut the ribbon transversely at equidistant points along the lines 2, Figure 2, said cuts severing one selvedged edge 1^b and extending to, 60 but not through, the opposite selvedged edge 1^a. The distance between these parallel cuts 2, is substantially equal to twice the width of the ribbon and thus forming rectangular sections of material 3 connected only by the 65 selvedge at one edge. A suitable cutting device is used for this purpose, the ribbon being fed therethrough in the usual manner.

The next operation consists of folding one half of each section of material 3, included between two cuts 2, 2 along a diagonal fold-line 4 (Figure 3) so that a triangular section 5^a of double thickness of material is formed throughout the right half of each section. It may be assumed that the folding 70 is accomplished by feeding the material lengthwise through a suitable folding machine, and in the direction indicated by the arrow, namely from left to right. In this manner the foremost corner of each section 75 3 is turned backward and the severed edge brought over into alignment with the unsevered selvedge edge 1^a. Carried on practically simultaneously with the folding operation, is a stitching operation whereby a 80 line of stitching 6 is carried along the unsevered edge, thereby sewing the parallel edge of each folded triangular section 5^a, to said selvedge edge 1^a. Manifestly the folding 85 precedes the sewing so that as each triangular portion is sewn in place it is folded down.

The third and final operation is that of folding the other half 5^b of each section 3, in the same manner as the previously folded 90 triangular half 5^a, and applying the binding strip B. This operation would be carried out on another machine, the partially completed material in the form shown in Figure 3, being fed through the machine in the reverse direction as shown by the arrow in Figure 4, namely from right to left.

Here again the foremost corners of the remaining unfolded halves of the sections 3, are folded back along diagonal fold lines 7 105 so that the severed edges 2, 2 which originally were at opposite ends of each section 3, are brought together at the center of the section, and the folded halves 5^a and 5^b are combined to form the complete section A. 110

As already suggested, the folding of the sections 5^b is followed closely by the applying and stitching of the binding strip B, this binding being of a suitable woven material preferably cut on the bias and into narrow strips.

The binding strip B, as clearly shown to the right in Figure 4, is hemmed on both edges, the edges being turned in, and the strip then applied around the unsevered edge of the folded ribbon, and finally stitched along the line 8, this line of stitching passing through the hemmed edges of the binding strip B, as well as the double thickness of the folded sections of the ribbon. It is to be observed that only the folded halves 5^a of the sections A are stitched down before the binding strip is applied, this being necessary in order to hold them in place during the final folding and stitching operation. The halves 5^b are stitched down with the application and sewing of the binding strip B.

From the foregoing description it follows that the resulting product forms an attractive and finished material suitable for the trimming of garments. With the various shades, textures, patterns and widths of ribbon available for use as the foundation, an endless variety of trimming may be produced.

In disclosing the material embodying the invention, I am aware that various forms and textures of braid, piping, and ribbon have been used for a similar purpose, but such materials when so used have been sewn directly to the garment in their natural form. I am not aware of a trimming in

which the ribbon or like material has been treated or fashioned to provide a pointed or scalloped edge, and a non-elastic binding applied along one edge, to give body and permanency to the material and serving as a foundation to be sewed to the material of the garment.

I therefore claim as new, any article of manufacture embodying the treatment of materials hereinbefore disclosed or suggested and more especially set forth in the appended claims.

I claim as my invention:

1. A garment trimming material as a new article of manufacture, comprising ribbon or like narrow textile material cut at equal intervals along parallel lines extending at right angles to one edge, the severed edges being folded back along diagonal fold lines to coincide with the unsevered edge of the material and a binding strip stitched along said unsevered edge.

2. A garment trimming material as a new article of manufacture, comprising ribbon or like narrow textile material cut along transverse lines terminating short of one edge thereof and spaced apart a distance substantially twice the width of the material, the severed edges being folded back upon the unsevered edge thereby forming triangular sections of double thickness of the material, and a binding strip stitched along the unsevered edge of the material and including the severed edges of the folded material.

In witness whereof, I hereunto subscribe my name this 27 day of Feby, A. D., 1923.

PERCY E. BROWN.
